CONVOLUTED ORNAMENT

Inventor: Charles A. Herold and Burt Lee, New York, N. Y., assignors to Paper Novelty Manufacturing Company, Inc., Brooklyn, N. Y., a corporation of New York

Application January 28, 1950, Serial No. 141,087

4 Claims. (Cl. 41—10)

1

The present invention relates to decorative ornaments and more particularly to decorative ornaments of the convoluted type that are used in long strands and thus are adapted to make garlands, festoons and streamers.

The general objects of the present invention are to provide a decorative ornament that will present a novel and pleasing appearance and a method for making such new decorative ornament that is extremely simple to operate and readily adaptable to mass production, whereby a decorative ornament embodying the present invention may be produced in large quantities in an extremely inexpensive manner.

The present invention relates to an improvement on the method set out in the patent to D. J. Kelman, Number 2,197,615. It is an object of the present invention to provide a method that will produce an ornament that will give the appearance of having alternating segments of different colors and thus present a pleasing and unusual effect.

It is also the object of this invention to provide a decorative ornament having all the qualities of sturdiness, neatness and attractiveness of an ornament previously made as set forth in the aforementioned patent and yet which has the additional quality of presenting a "two-tone" or striped appearance. The ornament may be formed in such a way that it appears to have alternating segments of different colors; thus it may be made to appear to have alternating segments of red and silver on blue and yellow. In another form the ornament may be prepared so that it appears to be one color when viewed from one position, and another color when viewed from another position.

It is another object of the present invention to provide a method of manufacturing an ornament embodying the present invention by a very simple method and one that is adapted for continuous operation to give an even flow of production of the novel ornament with no increase in labor cost or material cost being made necessary.

It is a still further object of the present invention to provide a method which can be practiced by using the apparatus for making the aforementioned type of ornament heretofore in use with only extremely small changes in such apparatus being necessary and yet producing a remarkably different and novel ornament.

These and other objects and advantages of the present invention will be more readily apparent from the following specification and drawing of specific embodiments of the present invention, in which drawing:

2

Fig. 1 is a partially broken away rear view of an apparatus illustrating the method embodying the present invention;

Fig. 2 is a side elevation thereof;

Fig. 3 and Fig. 4 are rear views of the crimping rollers showing the two positions of the foil;

Fig. 5 is a side elevation thereof;

Fig. 6 is a side elevation of the cam;

Fig. 7 is a schematic plan view of an entire apparatus illustrating the method embodying the present invention;

Fig. 8 is a side view of a decorative ornament embodying the present invention; and

Fig. 9 is a sectional view taken along line 9—9 of Fig. 8.

As is best seen in Fig. 7, which schematically sets forth an apparatus for practicing the novel method disclosed herein, a flat strip 10 of any suitable material customarily used in making convoluted ornaments, for example, paper, cellophane, or metal foil, may be first crimped or pleated by any conventional means. Although crimping of the material lends to the final product, a more pleasing appearance, it is not a necessary step in carrying out the new method. The material should have differently colored sides to produce an ornament having a striped or "two-tone" effect, and it is preferable to use metal foil since it is not translucent and will hold its shape more readily than the other materials customarily used. During or after crimping a core member is positioned on both sides of the flat strip. In the embodiment illustrated, a core member 12 is positioned above the flat strip 10 and a core member 13 is positioned below the flat strip. The core member may be made of cord, or any other flexible strand such as wire, string, or thread may be used.

The novelty of the present method resides in the positioning of the core members 12 and 13 relative to the longitudinal median line of the flat strip 10. It has been customary, heretofore, to position said core members along the longitudinal median line of the flat strip 10. In the method here presented, however, the core members 12 and 13 are positioned alternately on different sides of the longitudinal median line of the flat strip 10. As will be explained below, this produces the unexpected result of an ornament having a striped or "two-tone" effect if a flat strip 10 used has differently colored sides.

In the apparatus shown in Fig. 7, and Figs. 1 and 2, the core members 12 and 13 are fed into the crimping rollers 14 in a fixed position, and the flat strip 10 is shifted at intervals so that its longitudinal median line is alternately positioned.

on different sides of the core members 12 and 13. After crimping of the flat strip and positioning of the core members 12 and 13, they are twisted about their longitudinal axis thereby also twisting the flat strips 10 to form the convoluted ornament shown in Fig. 8; the twisting may also be directly applied to the strip 10 as well as to the core members 12 and 13 to insure more positive twisting of the flat strip 10.

An apparatus for practicing the novel method herein disclosed will now be considered in more detail.

Core members 12 and 13 are fed from spool 15 and 16 respectively. They lead from the spools 15 and 16 through guides 17, which position them above and below the flat strip 10, into grooves 18 in crimping rollers 14, as can best be seen in Figs. 3 and 4. The flat strip is fed from rolls 19 through guides 20 and then between the crimping rollers 14. The guides 20 are supported on one side by arm 21 and the other side they are slidably mounted on a support not shown. The arm 21 is slidably mounted in the supporting member 22 and terminates in roller 23, which engages in camway 24 formed by cam plates 25. The cam plates 25 are keyed to shaft 26 which is driven by a series of gears (not shown) which link the shaft 26 to the crimping rollers. The cam path 24 provided is one which reciprocates the arm 21 as the cam plate rotates; thus alternately positioning the thin strip 10 so that its longitudinal median line is positioned on alternate sides of the core members 12 and 13. The amount of the thin strip 10 that passes through the crimping rollers 14 on each position of the strip 10 can be varied by varying the gear linkage between the shaft 26 and the crimping rollers 14. The thin strip 10 with the core members 12 and 13 positioned in grooves 18 above and below it then passes through the crimping rollers 14 which are driven by belt 27 leading to a motor not shown; of course crimping is not necessary and this step may be omitted. Any means for positioning the core members 12 and 13 and the flat strip and holding them against rotation about a longitudinal axis may be used.

As shown in Fig. 7, the ends of the thin strip 10 and the core members 12 and 13 that emerge from the crimping rollers 14 are secured to hooks 28 carried on trolley 29. The trolley 29 has wheels 30 which ride on cables 31 as the material is fed through the crimping rollers 14, the trolley 29 is slowly pulled away from the crimping rollers 14 by means of cable 32. The cable 32 is hooked to the front of the trolley 29 at 33 it leads around drum 34 which is driven by means not shown, then up around a pulley not shown and is hooked on to the back of the trolley 29 at 35. The hooks 28 are spun rapidly by a motor, not shown, which is connected to wheel 36, which in turn drives the hooks 28 for rotary motion through bevel gears 37. The trolley 29 is moved away from the crimping rollers 14 by means of cable 32.

Fig. 8 shows a segment of an ornament embodying the present invention at one of the transition points where the ornament changes in appearance from one color to another. In this figure it is assumed that a flat strip having differently colored opposite sides has been used. One side being colored a color designated R (indicated by the vertical shading) and the other side being colored a color designated S. The transition point is located generally at the point indicated by bracket 38. When the ornament is viewed from a point to the left of a vertical plane the

segment 39 will appear to be colored R and the segment 40 will appear to be colored S. The color of the segments will appear just the opposite when the ornament is viewed from a point to the right of a vertical plane.

Assuming the twisting is counterclockwise as seen in Figs. 3 and 4, if the thin strip is fed between crimping rollers 14 with the R color side up, in the segment 39, the core members 12 and 13 would be to the left of the longitudinal median line as shown in Fig. 4, and in the segment 40 the core members 12 and 13 would be positioned to the right of the longitudinal median line as shown in Fig. 3.

If the core members 12 and 13 were always positioned along the longitudinal median line of the flat strip 10, all the curls 41 through 52 would be the same size. This has been the method heretofore in use. As can be seen in Fig. 8 at the transition point 38, where the core member is momentarily positioned along the longitudinal median line of the thin strip 10, as it moves from one side to the other, the curls 47 and 48 are equal in size. To the right of the transition point the odd numbered curls 41, 43, and 45 are small and the even numbered curls 42, 44, and 46 in effect hide and predominate over the small curls 41, 43, and 45. In the segment 39, the ornament will give the appearance of being colored the same way the large curls are colored, that is, it will appear to be the color R when viewed from the left and the color S when viewed from the right. In the segment 40, after shifting of strip to position, the core members 12 and 13 on the other side of the longitudinal median line, the odd numbered curls 49 and 51 have become the larger ones and they will hide or predominate over the smaller even numbered curls 50 and 52 and the segment 40 will thus appear S in color when viewed from the left and R in color when viewed from the right.

Thus, by the very simple method of alternately changing the position of the strip 10 relative to the core members 12 and 13, an ornament can be produced that presents a "two-tone" or striped effect.

Of course, if an ornament presenting an appearance of being of only one color when viewed from one side and of another color when viewed from the other side is desired, the shifting of the core members 12 and 13 from one side of the median line to the other side would be eliminated and the core members 12 and 13 would be positioned continuously to one side of the longitudinal median line of the strip 10.

We claim:

1. A decorative article comprising a strip of crimped sheet material the opposite sides of which are of different colors, and a wire on each side of said strip, both wires being disposed lengthwise with respect to said strip and offset laterally from the longitudinal centerline thereof equally distant in the same direction, said strip and said wires being twisted together on an axis comprising the portion of said strip between said wires, with portions of said strip on opposite sides of said axis extending radially from the axis of the twist forming two concentric helixes of different sizes staggered axially.

2. A decorative article comprising a strip of crimped metallic foil the opposite sides of which are of different colors, and a wire on each side of said strip, both wires being disposed lengthwise with respect to said strip and offset laterally from the longitudinal centerline thereof equally

distant in the same direction, said strip and said wires being twisted together on an axis comprising the portion of said strip between said wires, with portions of said strip on opposite sides of said axis extending radially from the axis of the twist forming two concentric helixes of different sizes staggered axially.

3. A decorative article comprising a pair of wires separated by a strip of sheet material, said wires being disposed lengthwise with respect to said strip and offset laterally from the longitudinal centerline thereof equally distant in the same direction, and said strip and said wires being twisted together with portions of said strip extending radially from the axis of the twist forming two concentric helixes of different sizes staggered axially.

4. A decorative article comprising a pair of filaments separated by a strip of sheet material, said filaments being disposed lengthwise with respect to said strip and offset laterally from the longitudinal centerline thereof equally distant in

the same direction, and said strip and said filaments being twisted together with portions of said strip extending radially from the axis of the twist forming two concentric helixes of different sizes staggered axially.
